(57) **CLAIM**

The ornamental design for a shoe sole with animal paws, as shown and described.

DESCRIPTION

FIG. 1 is a perspective view of a shoe sole with animal paws;
FIG. 2 is a left side view of FIG. 1;
FIG. 3 is a back view of FIG. 1;
FIG. 4 is a top view of FIG. 1;
FIG. 5 is a bottom view of FIG. 1;
FIG. 6 is a front view of FIG. 1; and,
FIG. 7 is a right side view of FIG. 1.

The broken lines shown in FIGS. 1-7 show environmental structure and form no part of the claimed design.

1 Claim, 3 Drawing Sheets
